UNITED STATES PATENT OFFICE.

SAMUEL JACKSON, OF PHILADELPHIA, PENNSYLVANIA.

IMPROVEMENT IN BREAKAGE-SIGNALS FOR RAILWAY CARS.

Specification forming part of Letters Patent No. 122,386, dated January 2, 1872.

To all whom it may concern:

Be it known that I, SAMUEL JACKSON, of the city and county of Philadelphia, in the State of Pennsylvania, have invented a new and useful Improvement in Breakage-Signals on Railroad Trains; and I do hereby declare the following to be a full, clear, and exact description thereof, which will enable others skilled in the art to which it appertains to make and use my improvement, reference being had to the accompanying drawing, which forms a part of this specification, and in which—

Figure 1, Sheet 1, is a side view of a railroad train provided with my improvement; Fig. 2, a perspective view of the apparatus when the flexible connection between the cars is severed; Fig. 3, Sheet 2, a vertical section of the signal-tube, water-tube, and air-pipe; and Fig. 4, a side view of the air-pipes, flexible connections, and couplings.

The same parts are denoted by the same letters in all the figures.

A A in the drawing represent the several sections of an open pipe or tube, which I prefer to make of iron, and which are attached in any convenient manner below the foot-board of the engine, the tender, and the cars. The several sections are connected by means of the flexible tubes B and the couplings C C'. The flexible tubes, which I prefer to make of India rubber, are drawn over the ends D of the pipe sections. These ends may be made conical or tapering so as to facilitate their insertion into the tubes B, and annular grooves or recesses may also be made at the base of each cone, into which grooves the ends of the rubber tubes shall contract, thus forming joints which are not only air-tight but may easily be drawn apart when the train is disconnected. These flexible tubes or hose should be long enough to allow for slack or play between cars, and not to be detached from the pipe A by the ordinary oscillations or lateral movements of the train. The tube B at the rear end of the train is closed air-tight by any suitable plug, E, as seen in Fig. 1, or the rear end of the pipe may itself be closed by an elastic or expansible plug. The section of pipe A, which is attached under the locomotive, is turned upward so as to enter a vertical tube or box

F. This tube, as well as the pipe, is open at top, and they have about the same height. The tube F should be kept filled with water to within a short distance of the top. G is the signal tube, closed at top and open at bottom, and of such diameter as to slide freely within the water-tube F.

The tubes F and G should be placed on some part of the locomotive where the signal-tube will be directly under the eye of the engineer. G may have a cap, flag, light, or any device attached to it which will render its descent, hereinafter explained, as conspicuous as possible; or it may be connected by any suitable mechanism with a bell, whistle, &c., so as to operate the same when it begins to descend.

In the operation of these devices, when a car is coupled to the train the plug E is withdrawn and the flexible tube at the rear of the train detached from the pipe A. The tubes B are then connected with the coupling, their outer ends drawn over the adjacent ends of pipe D D, and the coupling screwed up.

When the train has been made up the rear orifice of the section of pipe A on the rear car should be closed with a flexible tube and plug, as heretofore described, or in any other suitable way.

The train being coupled and ready to start, and the tube F filled with water to within a short distance of its top, the engineer inserts the signal-tube into it. The air within the signal-tube and pipe A is compressed by the weight of the signal-tube and sustains it in the elevated position shown in Figs. 1 and 3.

The breaking of an axle, the deviation of a car from the track, or any accident which causes a displacement of the train or a part thereof from its proper position, will withdraw one or more of the flexible tubes B from the pipe A and permit the air confined in said pipe to escape, so that the signal-tube, being no longer supported by such compressed air, will instantly descend and thereby notify the engineer of the accident.

What I claim as my invention, and desire to secure by Letters Patent of the United States, is—

1. A signal apparatus, so constructed that

the act of disconnecting the train shall operate the signal by permitting the escape of the air confined therein, substantially as described.

2. The combination of the air-pipe A extending along the train, the water-tube F, and the signal-tube G.

3. The combination of the signal-tube and

water-tube with the pipe A, constructed in sections, connected by flexible tubes.

SAMUEL JACKSON.
